UNITED STATES PATENT OFFICE.

ALEXANDER H. HANDLAN, JR., OF ST. LOUIS, MISSOURI.

ADJUSTABLE SUPPORT FOR SIGNAL-LAMPS.

No. 857,397.

Specification of Letters Patent.

Patented June 18, 1907.

Application filed November 12, 1906. Serial No. 343,038.

To all whom it may concern:

Be it known that I, ALEXANDER H. HANDLAN, Jr., a citizen of the United States of America, residing in the city of St. Louis, in the State of Missouri, have invented certain new and useful Improvements in Adjustable Supports for Signal-Lamps, of which the following is a full, clear, and exact description, reference being had to the accompanying drawings, forming part of this specification.

My invention relates to an adjustable support for signal lamps used upon railway cars, the invention having for its object to provide a support for such lamps that will permit of the lamp being lifted from its lower position, then adjusted in a lateral direction relative to the part of the car to which the support is applied, whereby the lamp may be disposed at the required angle or focus and then returned to its lower position.

My adjustable support is designed to take the place of rigid lamp supporting brackets heretofore in use and which are ordinarily fitted to sockets applied to railway cars. In view of the fact that the surfaces of the cars to which the bracket receiving sockets may be applied are irregular, it is difficult to so position the brackets and support the lamps at the required angles of foci, whereas such positioning of the parts is readily securable in the use of my adjustable support.

Figure I is a side elevation of my support with a lamp applied thereto. Fig. II is an enlarged vertical section taken through the support. Fig. III is a horizontal section taken on line III—III, Fig. II. Fig. IV is a view similar to Fig. II, illustrating a modification. Fig. V is a view similar to Fig. III, of the modification shown in Fig. IV.

A designates a signal lamp and B the wall of a car to which the lamp is adapted to be applied.

1 designates a socket that is secured to the car wall and 2 is a bracket arm which is seated in said socket. This bracket arm is provided with a horizontal wing 3 in the edge of which are a segmental series of openings 4.

5 and 6 are respectively upper and lower arms secured to the signal lamp, preferably through the medium of a vertical bracket plate 7 riveted or otherwise attached to the lamp shell.

8 is a pivot post that is vertically positioned in the arms 5 and 6 and to which the bracket arm 2 is loosely fitted for the purpose of permitting lateral swinging motion of

the arms 5 and 6 and the lamp when the pivot post is moved upward with the arms 5 and 6.

9 is a depending locking pin seated in the upper lamp carried arm 5 and projecting beneath said arm, in order that it may enter into either of the series of openings 4 in the wing 3 of the bracket 2 for the purpose of holding the lamp carried arms from movement relative to the bracket arm 2.

10 is a spring located between the lower lamp carried arm 6 and the bracket arm 2. This spring preferably surrounds the pivot post 8 and seats in a cavity in the bracket arm as seen most clearly in Fig. II. The spring serves to exert downward pressure upon said lower lamp carried arm with a result of holding the locking pin 9 in the pocket of the bracket arm wing 3, in which it has been seated, thereby preventing accidental dislodgment of said pin from said pocket due to the jarring of the lamp while the car that carries the lamp is in motion.

When it is desired to adjust the lamp in a lateral direction it is only necessary to lift the lamp and its arms 5 and 6 relative to the bracket arm 2, whereby the locking pin 9 is withdrawn from the pocket in which it was previously seated. The lamp may then be turned to the desired degree with the arms 5 and 6 moving on the axis provided by the pivot post 8 and when the desired lateral adjustment has been secured the lamp is returned to its lower position while the locking pin is permitted to enter into another of the pockets 4 of the bracket wing 3.

In Figs. IV and V, I have illustrated a modification in which the bracket arm wing 3' is shown provided with a segmental series 95 of openings in the form of pin-holes 4' in lieu of the open openings 4 to receive the locking pin 9. In this construction the spring 10 is dispensed with. The remaining parts of the support are similar to those previously described and the action thereof is the same as in the first recited construction, with the exception that no means is provided to prevent displacement of the locking pin 9 from the bracket arm wing, due to jarring of the car to which my lamp support may be applied.

I claim:

1. A supporting bracket for signal lamps comprising a bracket arm having a horizontal wing formed with a segmental series of openings, a bracket plate having upper and

lower arms spaced apart a greater distance than the height of the bracket arm and between which the bracket arm with its wing projects, a vertical pivot post adapted to slide vertically in the bracket arm and connecting the upper and lower arms and secured thereto, and a depending pin secured to the upper arm and adapted to engage one of the series of openings in the wing when the upper arm is seated upon the wing and to be released from the opening when the upper arm is raised from the wing to enable the lamp to be moved laterally.

2. A supporting bracket for signal lamps comprising a bracket arm having a horizontal wing formed with a segmental series of openings, a bracket plate having upper and lower arms spaced apart a greater distance

than the height of the bracket arm and between which the bracket arm with its wing projects, a vertical pivot post adapted to slide vertically in the bracket arm and connecting the upper and lower arms and secured thereto, a spring coiled around the pivot post between the bracket arm and the lower arm, and a depending pin secured to the upper arm and adapted to engage one of the series of openings in the wing when the upper arm is seated upon the wing and to be released from the opening when the upper arm is raised from the wing to enable the lamp to be moved laterally.

ALEXANDER H. HANDLAN, JR.

In presence of—

NELLIE V. ALEXANDER,
BLANCHE HOGAN.
